UNITED STATES PATENT OFFICE.

CHARLES O. SMITH, OF SAN JOSE, CALIFORNIA.

COOKER.

1,411,811.

Specification of Letters Patent. Patented Apr. 4, 1922.

Application filed June 2, 1920. Serial No. 385,949.

To all whom it may concern:

Be it known that I, CHARLES O. SMITH, a subject of Great Britain, and a resident of the city of San Jose, county of Santa Clara, State of California, have made a new and useful invention—to wit, Improvements in Cookers; and I do hereby declare the following to be a full, clear, concise, and exact description of the same.

10 This invention relates more particularly to cookers used in the canning art, wherein the filled cans are advanced through the heating medium from the intake to the discharge end.

15 Among the objects of the invention are to provide a new and efficient method for carrying on the cooking of the cans in a continuous process, to guard against the escape of steam and heat through the intake and discharge ports and to provide a simple 70 and convenient method and means for opening the discharge ports and removing and discharging the cans upon the completion of the cooking operation. Further objects 75 20 and 25 are raising the efficiency of operation with a decreased cost of maintenance by minimizing the expenditure of energy and reducing the liability of burning or scalding an operator by the escape of the heating medium. 80 30 Other objects and advantages will appear as this description advances.

In this specification and the annexed drawings, the invention is illustrated in the form considered to be the best but it is to be understood that the invention is not limited to such form, because it may be embodied in other forms; and it is also to be understood that in and by the claims following the description, it is desired to cover the 85 40 invention in whatsoever form it may be embodied.

In the accompanying two sheets of drawings—

Fig. 1 is a side elevation of a cooker constructed in accordance with my invention and having my new and improved discharge chute applied thereto.

Fig. 2 is a vertical section taken through the discharge on the line 2—2 of Fig. 1.

50 Fig. 3 is a side elevation of the discharge taken on the line 3—3 of Fig. 1.

Fig. 4 is a plan section taken on the line 4—4 of Fig. 1 through a discharge with the gate closed.

55 Fig. 5 is view similar to Fig. 4 with the

discharge opened and the neck of the receiver applied thereto.

Fig. 6 is a side elevation through a modified form of discharge, taken on the line 6—6 of Fig. 8. 60

Fig. 7 is a vertical section through the modified form of discharge taken on the line 7—7 of Fig. 8.

Fig. 8 is a side elevation of a modified form of cooker having an individual discharge chute applied to each of the discharge ports of the cooker. 65

In detail the construction illustrated in the drawings includes the heating box 1 into which a suitable heating medium such as live steam, hot air or water is passed through the conduit 2. The ends of the heating box 1 are provided with suitable enclosing plates 3 and 4 drilled to provide bearings for the ends of the shaft 5, extending concentrically 70 through the box 1, and having a can carrying frame 6 thereon. The can carrying frame 6 is rigidly mounted upon the shaft 5, in a manner not shown, and comprises a cylindrical body portion having radially extending division walls 7 helically wound around said body frame 6, having transverse division plates 8 interposed between the helical division members. The space between the body portion of the can carrying frame 85 6 and the inner wall of the heating box 1 is slightly greater than the diameter of cans being passed through in the cooking operation. 80

One end of the shaft 5 is provided with a 90 worm wheel 9 meshing with a worm 10, operated by a motor or other prime mover, not shown, providing an efficient means for slowly rotating the can carrying frame, to provide the necessary time interval for cooking the product in the cans. The heating box 1 is provided with an inlet port 11 of any suitable type for admitting cans into the cooker and into position on the can frame 6. Thus when the carrying frame 6 100 is rotated by the driving mechanism on the shaft 5, the cans fed into the division chute of the frame 6, it follows that cans introduced through the inlet 11 at one end of the box will be advanced through it, by rotation of the said frame, to the discharge end, and that by admitting a series of cans a continuous cooking operation can be carried on. 105

The particular form of cooker that I have 110

adopted is of a type standard to the canning trade, permitting all cans to be cooked to be introduced through one inlet port and to be discharged from the heating box at any 5 one or at all of the plurality of discharge outlets according to the length of cooking period it is desired to give the various cans. Thus if it is desired to give certain cans a long period cook to be followed by short 10 period cook cans, the first of the short cook cans can be admitted to the heating box immediately and without loss of time, after the last of the long cook cans, and when the first of the short cook cans reaches its point 15 of discharge, the gate at that point can be opened and the short cook cans discharged, while the last of the long cook cans having already passed this point will proceed to its own discharge gate. To provide a new, efficient and effective discharge chute for receiving the cooked cans from the heating box I have provided a novel apparatus that may be moved into and from connection with any one of the plurality of discharge openings 20 in the heating box, and which will automatically open and close the discharge gates in being placed into and from operative position.

The automatic discharge chute comprises 25 a hollow neck portion 14 having a receiving end adapted to fit the contour of the heating box. The neck of the receiving end is provided with male projections 15 and 16 on opposite sides thereof for the purpose of 30 engaging in female grooves 17 and 18, formed in the slide plates 19 and 20 secured to the outside of the heating box along the edges of the discharge outlet therein. The 35 opposite end of the neck portion 14 is provided with a substantially annular casing 21 having an outlet 22 therein. The interior of the casing 21 has the segmental rotor 23 revolvably mounted therein on the shaft 24. The rotor 23 is provided with chambered 40 depressions 25 to function as cradles in receiving the cans discharged from the heating box and to regulate the time interval of discharge of the cans from the cooker.

The shaft 24 is preferably formed square 45 to slidably engage with a squared bushing 26 rotatively retained with the rotor 23, permitting the rotor and enclosing casing to be slidably adjusted on the shaft and into engagement with any one of the discharge ports. The shaft 24 is mounted in the supporting bearings 27, 28 and 29 and is rotated by the pulley 30 fixed thereon and connected by means of a suitable belt or silent chain with the pulley 31 mounted on 55 the driven worm wheel shaft 5. The lower depending rotor casing on the discharge neck has the supporting wheel 32 rotatably mounted thereon and guided on the rail track 33 secured to the base support, thus 60 aiding in moving the discharge chute from one outlet to the next.

aiding in moving the discharge chute from 65 one outlet to the next.

The discharge chute is applied to the outlet gates in the following manner: Assuming that the receiving neck is resting against the heating box between any pair 70 of the outlets 34, 35 or 36, the operator grasps the neck in his hands and lifts it away from contact with the heating box at the same time sliding it along toward the outlet desired. When the desired location 75 is reached the male slide projections 15 and 16 are slidably engaged with the grooves 17 and 18 in the plates 19 and 20, and moved along into engagement with the gate 37, normally adapted to close the individual 80 heating box outlet. As the gate 37 slowly uncovers the outlet the receiving neck gradually covers it until the throat chute 14 positions itself to receive the discharge from the can carrying tray in the interior of the 85 heating box. The receiving chute is only placed in position at about the time the first can of a cook is timed to be discharged. At this interval the operator grasps the handle 39 pivoted to the neck casing at 40, 90 throwing the squared dog clutch 41 slidably mounted on the shaft 24 into engagement with the serrated face on the bushing 26 and starting the rotor 23 revolving. Thus the cans roll away from the shelves on the 95 can carrying frame out through the discharge outlet and neck 14 into the cradle formed rotor 23 and out through the can discharge 22 into conveyors or boxes from whence they are transported to benches for 100 labeling or packing.

Upon the termination of the discharging operation the receiving neck is disengaged from the guide plates and moved away from the discharge orifice. As the neck slides out 105 of position the closing gate by reason of the tension of the spring 41 follows closely thereafter closing the outlet and preventing heat and steam from escaping from the interior of the cooker.

A modified form of cooker and discharge outlet is illustrated in Figures 6, 7 and 8. The modification consists in applying a separate and independent discharge mechanism 110 50, 51, and 52 to each of the heating box outlets 34, 35 and 36 by securing the neck or receiving portion 14 thereof rigidly to the shell of the heating box 1. The shaft 24 continues through each of the rotary can receiving casings and operates continuously, 115 enabling an operator to operate at will any particular mechanism by moving the pivoted control handle 39 to engage the slidably splined dog clutch 41 with the clutch bushing 26 on the rotor 23.

The receiving throat of the hollow neck portion 14, adjacent each of the box outlets 34, 35 or 36, is enlarged as at 42 and has

the slide gate 43 mounted therein. The gate 43 has the gear rack 44 mounted thereon and meshing with a pinion 45 fixed on a shaft 46 that is mounted in a bearing 47 in the 5 wall of the casing 14. The handle 48 is swivelly mounted on the end of the shaft 46 and provides a means by which an operator may open the discharge gate 43 through the pinion 45 and rack 44 when it is desired 10 to receive cooked cans from the heating box.

Where the heating box outlets are provided with the independent, stationary discharge mechanisms the liability for losing 15 cooking steam or heating medium is lessened to a considerable extent, as are the dangers that might arise from the escaping steam burning the hands or body of an operator. Discharge mechanisms such as described 20 are also especially advantageous for controlling the rate of discharge of the cooked cans, eliminating any disastrous results that occur where cans pile up and jam when they are permitted to be discharged 25 by gravity. A synchronous operation between can carrying frame and can discharge rotor, thus provided, serves to positively regulate and control the movement of the cans from the cooker at predetermined and 30 regular intervals.

Having thus described my invention what I claim and desire to secure by Letters Patent is:

1. In a cooker, the combination with a 35 heating box having a can inlet and a series of discharge ports at successively increasing distances from the inlet; gates covering said 40 ports of means for passing the cans through the cooker to the discharge ports; means whereby cans can be discharged through any particular outlet and an independently operable mechanism adapted to displace the gate covering said outlet for receiving the cans discharged from any one of the series of 45 outlets.

2. In a cooker, the combination with a heating box having a can inlet and a series of discharge ports at successively increasing distances from the inlet; gates covering said 50 ports of means for advancing the cans through the cooker to the discharge ports; means whereby cans can be discharged through any particular outlet and a mechanism adapted to displace the gate covering 55 said outlet for receiving the discharged cans adapted to be operable synchronously with the can advancing means.

3. In a cooker, the combination with a heating box having a can inlet and a series 60 of discharge ports at successively increasing distances from the inlet; gates covering said ports of means for advancing the cans through the cooker to the discharge ports; means whereby cans can be discharged 65 through any predetermined outlet and a

mechanism adapted to displace the gate covering said outlet for receiving discharged cans, movable relative to the series of discharge ports.

4. In a cooker, the combination with a 70 heating box having a can inlet and a series of discharge ports at successively increasing distances from the inlet; gates covering said ports of means for advancing the cans through the cooker to the discharge ports; means whereby the cans can be discharged through any predetermined outlet and a mechanism adapted to displace the gate covering said outlet for receiving discharged cans adapted to be operable synchronously 80 with the can advancing means and movable relative to the series of discharge ports.

5. In combination with a cooker such as described having a plurality of discharge outlets, of means within the cooker for advancing cooked cans to said outlets; an independent gate covering each of said outlets and a portable discharge mechanism adapted to be placed into operative position relative to any predetermined outlet and displacing 90 said gate covering said outlet.

6. In combination with a cooker such as described having a plurality of discharge outlets, slide gates covering said outlets of means within the cooker for advancing 95 cooked cans to said outlets; a portable discharge mechanism adapted to be placed into receiving position relative to any predetermined outlet and displacing the slide gate covering the same and means for synchronously 100 driving the can advancing means and discharge mechanism.

7. In a cooker, the combination with a heating box having a can inlet and a plurality of discharge ports at successively increasing 105 distances from the inlet, independent slide gates covering each of said ports, of a can carrying frame rotatably mounted within said heating box; a helically mounted division plate on said frame for advancing 110 the cans to the discharge ports; means whereby cans may be discharged through any particular outlet and a portable mechanism adapted to displace the slide gates covering said outlet for receiving the cans 115 adapted to be attached to or detached from any predetermined outlet.

8. In a cooker, the combination with a heating box having a can inlet and a plurality of discharge ports at successively increasing 120 distances from the inlet; independent slide gates covering each of said ports, of a can carrying frame rotatably mounted within said heating box; a helically mounted division plate on said frame for advancing 125 the cans to the discharge ports; means whereby cans may be discharged through any predetermined discharge port; a portable mechanism for receiving the cans adapted to displace a predetermined slide 130

- gate and to be attached to or detached from the said discharge port and means for synchronously operating the can carrying frame and discharge receiving mechanism.
- 5 9. In combination with a cooker having a can inlet and a series of discharge ports, and means for advancing the cans through the cooker from the inlet to the discharge ports; gates covering each of said discharge ports
- 10 and an independently operable mechanism adapted to receive the cans from said discharge ports, comprising, a neck portion adapted to displace the gate from a predetermined discharge port and register therewith and means for operating said mechanism in unison with the can advancing means of said cooker or independently thereof.
- 15 10. In combination with a cooker having a can inlet and a plurality of discharge ports, and means for advancing the cans through the cooker from the inlet to the discharge ports; gates covering each of said ports; a can discharge mechanism adapted
- 20 to receive the cans from any discharge port of said cooker, comprising, a conduit adapted to displace the gate from a predetermined discharge port and register therewith and a clutch for operating said mechanism in unison with the can advancing means of said cooker or independently thereof.
- 25 11. In combination with a cooker having a can inlet and a plurality of discharge ports, and means for advancing the cans
- 30
- 35
- through the cooker from the inlet to the discharge ports; guides adjacent said ports; gates mounted in said guides and covering each of said ports; a can discharge mechanism adapted to receive the cans from any discharge outlet of said cooker, comprising, a conduit engageable with the guides on said cooker and adapted to displace the gate from a predetermined discharge port and register therewith and means for operating said mechanism in unison with the can advancing means of said cooker or independently thereof.
12. In combination with a cooker having a can inlet and a plurality of discharge ports, and means for advancing the cans through the cooker from the inlet to the discharge ports; guides adjacent said ports; gates mounted in said guides and covering each of said ports; a can discharge mechanism adapted to receive the cans from any discharge outlet of said cooker, comprising, a conduit engageable with the guides on said cooker and adapted to displace the gate from a predetermined discharge port and register therewith; a cylinder within said mechanism and means for rotating said cylinder in unison with the can advancing means of said cooker or independently thereof.
- In testimony whereof, I have hereunto set my hand at San Francisco, California, this 28th day of May 1920.
- CHARLES O. SMITH.
